CAMP STOVE

James K. Derden, Wharton, Tex., assignor of
one-half to George P. Willis, El Campo, Tex.
Application October 16, 1950, Serial No. 190,427

1 Claim. (Cl. 126—25)

1 This invention relates to new and useful improvements in camping equipment and more specifically to camping stoves.

The primary object of the present invention is to provide a camp stove including a casing open at its top and a perforated baffle plate slidable into the casing between the open top of the casing and the bottom wall of the casing to restrict the passage of hot air, in the casing, from passing from the open top of the casing.

Another important object of the present invention is to provide a camp stove including a casing in which coals are to be burned and a frame hinged to the casing for vertical swinging movement and supporting a grid member that will support articles over the casing.

A further object of the present invention is to provide a portable stove of the aforementioned character wherein the frame is composed of vertical walls that extend well above the grill to shield articles on the grill from the wind.

A still further aim of the present invention is to provide a camp stove that is composed of sheet metal members to reduce the over-all weight of the stove and to permit carrying or transporting of the stove in a convenient manner, and which will also permit the stove parts to be quickly and readily cleaned.

Other objects and advantages reside in the details of construction and operation as more fully hereinafter described and claimed, reference being had to the accompanying drawings forming part hereof, wherein like numerals refer to like parts throughout, and in which:

Figure 1 is a perspective view of the invention showing the shielding plate disposed exteriorly of the burner box and with dotted lines showing the shielding plate raised and the grill support also raised;

Figure 2 is a vertical sectional view taken substantially on the plane of section line 2—2 of Figure 1; and

Figure 3 is an enlarged detail sectional view showing the shielding baffle plate partially moved into the burner box or casing.

Referring now to the drawings in detail, wherein for the purpose of illustration, there is disclosed a preferred embodiment of the present invention, the numeral 10 represents an elongated substantially rectangular fire box or casing including a forward wall 12, a rear wall 14, end walls 16 and 18, and a bottom wall 20.

The lower corners of the walls 12, 14, 16 and 18 are integrally formed with depending vertical extensions 22 forming legs. The forward exten-

2 sions 22 of the end walls are welded to the extensions 22 of the forward wall and the rear extensions 22 of the end walls are welded to the extensions 22 of the rear wall. The adjacent edges of the walls 12, 14, 16 and 18 are also welded together and the bottom wall 20 is welded to the walls 12, 14, 16 and 18.

The forward legs 24 of the stove are connected to the rear legs 26 of the stove by transverse skids 28 having upwardly curved end portions 30 whereby the entire unit may be readily slid over the ground to a desired location and so that the stove may be swung about as the wind and circumstances may require.

Horizontal angle iron guides 32 are mounted on the inner faces of the end walls and extend between the forward and rear walls. The upper surfaces of the guides 32 are flush with the lower horizontal edge 34 of an elongated horizontal slot 36 in the forward wall 12 and the ends of the slot 36 communicate with the forward ends of the guides.

A substantially rectangular and perforated shielding or baffle plate 38 forms a major part of the invention and includes an upper edge 40 having lateral extensions that are bent to form hanger hooks 42. The hooks enter the slot 36 and engage over the edge 34 to support the plate 38 vertically at the front of the casing and against the forward wall 12. Hand grips 44 are mounted on the lower edge of the plate 38 whereby the plate may be manually raised, in the direction of arrows R, and then slid through the opening or slot 36 and on the guides 32 in the casing 10, in the direction of arrows I in Figures 1 and 3.

The rear wall 14 is provided with a series of small holes 46 so that air may enter the casing in assistance to the fire and the bottom wall 20 is also provided with a series of holes 48 so that moisture or water, rain or otherwise, can drain readily from the fire box or casing 10. The end wall 18 is formed with an access or ash removal opening that is closed by a door 50 which is hinged to the end wall 18. Swingable latch arms 52 mounted on the wall 18 overlie the door 50 and normally retain the door in its closed position.

A U-shaped frame or grill support 54 is supported on the casing 10 and includes a rear vertical wall or web portion 56 and vertical end walls or leg portions 58 and 60. The walls 58 and 60 are flush with and form extensions of the walls 16 and 18, and the wall 56 is flush with and forms an extension of the wall 14 when the support 54 is lowered against the casing 10.

3

The rear wall 56 of the support 54 is hinged, as at 62, to the rear wall 14 of the casing 10 to permit vertical swinging movement of the support 54 relative to the casing 10 as shown by arrows A.

The member 54 supports a rectangular angle iron frame member 64 on which there is mounted a grid or grill 66. The grill 66 may be hardware cloth or any similar type material and is welded in place at all contact points, to the frame member 64. A hand grip 68 is fixed to the forward rail of the frame member 64.

In practical use of the invention, a fire is built in the box 10 and the support 54 lowered against the casing 10. The walls 56, 58 and 60 will retain articles relative to the grill 66 during raising and lowering of the support 54 and these walls 56, 58 and 60 also act as wind shields.

The plate 38 is raised and moved into the casing to separate the grill from the fire and the openings in the plate 38 permit some of the hot air rising in the casing to pass through the plate 38 to contact food on the grid 66.

It should be noted that the shielding plate 38 provides the positive heat control method inasmuch as it will function as a damper or baffle. Also, the leg supports 22 may be hinged to the end walls so that they may be folded in toward the center and thereby provide a more compact unit for transportation purposes.

A lightweight top T for the entire unit is hinged to the rear wall 56 and may be lifted all the way over so that when not in use it simply hangs down toward the ground at the back of the unit. When the top T is in use, it will rest on top of the U-shaped frame or grill support 54. The top will prevent the escape of smoke and heat and it will provide much greater efficiency in cooking.

In view of the foregoing description taken in conjunction with the accompanying drawings it is believed that a clear understanding of the construction, operation and advantages of the device will be quite apparent to those skilled in this art. A more detailed description is accordingly deemed unnecessary.

It is to be understood, however, that even though there is herein shown and described a preferred embodiment of the invention the same is susceptible to certain changes fully comprehended by the spirit of the invention as herein described and the scope of the appended claim.

4

Having described the invention, what is claimed as new is:

A camp stove comprising a casing forming a combustion chamber and including a forward wall, a rear wall, a pair of end walls and a bottom wall, said bottom wall adapted to form a fuel support, said casing having forward and rear supporting legs, said legs having outer walls that are flush with said forward and rear walls, a pair of guides mounted on said end walls spaced above said bottom wall and extending between said forward and rear walls, said forward wall having an elongated horizontal slot therein extending between said guides and in line therewith, a perforated baffle plate slidable in said slot and on said guides, hooks carried by the plate at its rear edge engaging the lower edges of the slot to support the plate vertically from the forward wall when the plate is moved forwardly out of the slot, said slot being spaced vertically from the lower ends of said legs a distance greater than the length of said plate whereby said plate will rest against said forward legs and front wall when it is withdrawn from the slot, a U-shaped frame overlying the casing and including a web portion and a pair of leg portions integrally formed with and joined by said web portion, hinges securing the web portion of said frame to said rear wall, and a grid member secured to and confined within said frame in overlying relation to said casing, said baffle plate positioned between the bottom of said casing and grid to regulate the amount of heat passing to the grid.
